UNITED STATES PATENT OFFICE.

LOUIS S. MILLER, OF NEW YORK, N. Y.

MUSIC-LEAF TURNER.

SPECIFICATION forming part of Letters Patent No. 761,524, dated May 31, 1904.

Application filed December 15, 1903. Serial No. 185,225. (No model.)

To all whom it may concern:

Be it known that I, LOUIS S. MILLER, a citizen of the United States, and a resident of the city of New York, borough of Brooklyn, in the county of Kings and State of New York, have invented a new and Improved Music-Leaf Turner, of which the following is a full, clear, and exact description.

This invention relates to improvements in devices for turning sheets or leaves of music, the object being to provide a device for this purpose that will be simple in construction and inexpensive and that may be easily adapted to a piano or similar instrument or to a music-rack and by means of which the leaves of music may be consecutively turned without interfering with a person's playing.

I will describe a music-leaf turner embodying my invention and then point out the novel features in the appended claims.

Reference is to be had to the accompanying drawings, forming a part of this specification, in which similar characters of reference indicate corresponding parts in all the figures.

Figure 1 is a front elevation of a music-leaf turner embodying my invention, showing it as attached to a piano. Fig. 2 is a sectional view showing the turning mechanism. Fig. 3 is an elevation showing the releasing mechanism employed. Fig. 4 illustrates a leaf-supporting frame attachment that may be employed when the device is not used in connection with a music-rack or piano. Fig. 5 shows the end of one of the turning-arms. Fig. 6 is an end view of a single-sheet holder that may be employed. Fig. 7 is a perspective view of an operating-lever that may be used. Fig. 8 is a section on the line $x-x$ of Fig. 2, and Fig. 9 is a section on the line $y-y$ of Fig. 4.

The music-leaf turner comprises a cylinder 1, having a removable top 2, and extended upward through the cylinder is a shaft 3, on the upper screw-threaded end of which are clamping nuts or plates 4 5, engaging, respectively, with the upper and lower side of a clip-plate 6, designed to engage with the base-board 7 of a music-rack. As here shown, this clip 6 consists of a plate of metal folded to form upper

and lower members, (see Fig. 9,) and preferably it will be provided with a lining 8, of soft material, such as felt, to prevent marring of the music-rack.

Mounted to rotate on the shaft 3 is a sleeve 9, and rotating on the sleeve 9 is a sleeve 10, while a sleeve 11 rotates on said sleeve 10. The upper or outer end of the sleeve 11 is attached to a disk 12, which bears upon the top 2 of the cylinder. A similar disk 13 is attached to the outer end of the sleeve 10, while a disk 14 is attached to the upper end of the sleeve 9. A coiled spring 15 is attached at its inner end to the sleeve 9 and at its outer end to a cup 16, in which the spring is placed. Springs 17 18 are connected, respectively, to the sleeves 10 11 and are arranged in cups 19 20 and are connected at their outer ends to said cups.

As clearly shown in Fig. 8, the cups are provided at one side with openings, the walls of which engage at the opposite sides of a rib 21, formed on the inner side of the cylinder, and thus the cups are held from rotary motion, and by referring to said Fig. 8 it will be seen that one wall of the cup is turned over or formed into a hook 22, with which the end of the spring engages. By thus arranging the springs they, with the cups and sleeves, may be readily removed from the cylinder when necessary for repairs and as readily assembled therein.

Extended outward from the disks 12, 13, and 14 are arms 23 24 25. The end of each arm is provided with a double coil 26, and between the coils a music-leaf is designed to be inserted. Secured to one side of the cylinder is a casing 27, movable vertically, in which is a holding-bar 28, designed to hold the leaf-engaging arms in one position against the resistance of their springs. This holding-bar moves through openings in the top and bottom walls of the casing, and at one side it is provided with a series of notches 29, corresponding to the number of turning-arms, and it may be here stated that while I have shown but three turning-arms more than this number may be employed, if desired.

Arranged to swing in the casing is an arm

30, which is held yieldingly upward by means of a spring 31, and pivotally connected to the arm 30 is an escapement-lever 32, the lower tooth 33 of which is designed to engage the 5 walls of the notches 29, as will be hereinafter described. The outer portion of the escapement-lever engages with a finger 34, extended laterally from the arm 30. This lever 32 may be provided with a finger-piece 35, on which 10 a person may place his fingers to move the lever downward; but preferably the movement of the lever is caused by the pressure of the player's knee, and therefore I attach a chain 36 to the lever, and this chain passes down 15 through an opening in the keys or between two of the keys of a piano and through an opening formed in the key-box and connects at its lower end with a crank-lever 37, mounted to swing on the lower side of the key-box. Obviously by forcing the depending portion of 20 this lever 37 laterally the part at right angles thereto and engaging directly with the chain will be swung downward, consequently pulling the lever 32 downward.

25 Extended upward from the nut 4 is a plate 38, designed to be placed against the rear of the music-sheets at the center, and extended upward from the part 3 is a rod 39 for engaging with the sheets at the front and at the 30 center.

In the operation of the device as so far described the several arms are to be turned to the right and connected with consecutive leaves of music. The bar 28 when moved 35 upward will engage against the front sides of the several arms and will be held in its elevated position by the pressure of the arms. When it is desired to turn a leaf, the escapement-lever, with the arm 30, is to be moved 40 downward, so that the tooth 33 by engaging with the lower wall of a notch will move the rod downward to release the upper arm. Upon releasing the pressure the spring 31 will move the arm 30 and the escapement-lever back to 45 normal position, and then the upper tooth of the escapement-lever by engaging with the bar or casing will limit the upward movement. Then to turn the sheet held by the second arm the bar 28 is to be moved downward 50 one step, as before mentioned.

As a means for holding a single sheet of music I provide an attachment consisting of a metal strip 40, having its upper and lower ends folded to form clip portions 41, between which 55 the edge of the single sheet may be secured, and these clip portions are also designed to engage around the rod 39. It may be sometime necessary to use the device under other conditions than securing the same to a piano, 60 as heretofore mentioned. In other words, I have provided a means for supporting the device on a table or the like, which consists of a frame comprising side bars 42 43, which at the lower ends have threaded extensions 44,

which pass through openings in the upper and 65 lower members of the fastening device 6, and engaged with these threaded portions are legs 45, having rubber buttons or cushions 46 at their lower ends. The upper ends of the rods 42 43 are removably connected to a cross-bar 70 47. As here shown, the said bars 42 43 have interior screw-threads at the upper ends, which are engaged by headed bolts 48, which pass through openings in the cross-bar 47.

Having thus described my invention, I claim 75 as new and desire to secure by Letters Patent—

1. A music-leaf turner comprising a cylinder, a shaft extended upward through the cylinder, a plurality of sleeves mounted to rotate around the shaft, cups supported by the 80 sleeves, springs attached at their inner ends to the sleeves and at their outer ends to the cups, means for preventing rotary movement of the cups in the cylinder, sheet-turning arms carried by the sleeves, and holding and releasing devices for the turning-arms. 85

2. A music-leaf turner comprising a cylinder having a rib on its inner side, a shaft extended upward through the cylinder, a plurality of sleeves arranged one upon another 90 around said shaft, cups supported by the sleeves and having openings at one side, the walls of which engage with said rib, springs attached at their inner ends to the sleeves and at their outer ends to the cups, sheet-turning 95 arms carried by the sleeves, and holding and releasing means for the arms.

3. A music-leaf turner comprising a cylinder adapted to be secured to a music-rack or the like, a plurality of sheet-turning arms, 100 sleeves arranged in the cylinder and carrying said arms, said sleeves being mounted to rotate independently one of another, springs for causing the rotation of the sleeves, a casing on one side of the cylinder, a notched bar movable vertically through the casing for engaging with the turning-arms, a spring-pressed holding-arm pivoted in the casing, a finger on 105 said arm, and an escapement-lever pivoted to said arm and adapted to engage said finger the 110 said escapement-lever having a finger-piece. 115

4. A music-leaf turner comprising a cylinder, a shaft extended upward through the cylinder, a clamping device attached to the shaft, sleeves mounted to rotate around the shaft, the 115 said sleeves being placed one upon the other, disks upon the upper ends of the sleeves, leaf-turning arms extending from the disks, a casing arranged on one side of the cylinder, a notched bar movable vertically through said 120 casing for engaging the turning-arms, a spring-pressed holding-arm pivoted in the casing, an escapement-lever pivoted to the said arm, and an operating-chain attached to the escapement-lever the said escapement-lever having 125 a finger-piece.

5. A music-leaf turner comprising a cylinder, spring-actuated leaf-turning arms mount-

ed on the cylinder, a clamping-plate attached to the cylinder and having openings, a frame comprising side uprights having threaded portions extended through said openings, legs en-
5 gaging with said threaded portions, and a cross-
bar removably connected to the upper ends of
the said uprights.

In testimony whereof I have signed my name to this specification in the presence of two sub-
scribing witnesses.

LOUIS S. MILLER.
